UNITED STATES PATENT OFFICE.

GILBERT L. CROWELL, JR., OF ARLINGTON, NEW JERSEY, ASSIGNOR TO C. R. SMITH & SON, OF PHILADELPHIA, PENNSYLVANIA.

DESIGN FOR A SPOON.

SPECIFICATION forming part of Design No. 20,844, dated June 23, 1891.

Application filed May 25, 1891. Serial No. 394,069. Term of patent 7 years.

To all whom it may concern:

Be it known that I, GILBERT L. CROWELL, Jr., a citizen of the United States, residing at Arlington, in the county of Hudson and State 5 of New Jersey, have invented and produced a certain new, useful, and original Design for Spoons, of which the following is a specification, reference being had to the accompanying drawings.

- 10 Figure 1 is a front view of the spoon. Fig. 2 is a rear view of the spoon.
The general outline of the handle of the spoon is wavy or recurring, the slight convexities and concavities on one side edge being 15 opposite those on the opposite side. The upper widest portion of the handle merges gradually into the shank portion. At the top of the handle is the representation of a keystone A, and at the edge of the handle and 20 following the outline thereof is a raised border-bead B. This keystone and the bead are shown on the back of the handle also. Upon the front face of the handle at the upper end is the representation of a man's head and shoulders C. At the lower end of the shank 25 is a representation of a bell D, the outline of which joins the outline of the shank and the outline of the bowl, the lower part of the bell forming, apparently, a part of the bowl. This bell is represented on both the front and the 30 rear sides of the spoon handle and bowl. In the bowl of the spoon is represented a building E, which in general character is like to a public building. The back of the spoon and bowl is plain except for keystone A, the bead 35 B, and the bell D.

What is claimed as new is—

1. The design for spoons, substantially as herein shown and described.
2. In the design for spoons herein shown 40 and described, the front thereof.
